UNITED STATES PATENT OFFICE.

JOSEPH L. STENGEL, OF CINCINNATI, OHIO, ASSIGNOR TO UNION SPECIAL MACHINE COMPANY, OF CHICAGO, ILLINOIS, A CORPORATION OF ILLINOIS.

TAPE-GUIDE FOR SEWING-MACHINES.

1,255,243.

Specification of Letters Patent.

Patented Feb. 5, 1918.

Application filed February 9, 1917. Serial No. 147,593.

To all whom it may concern:

Be it known that I, JOSEPH L. STENGEL, a citizen of the United States, residing at Cincinnati, in the county of Hamilton, State 5 of Ohio, have invented certain new and useful Improvements in Tape-Guides for Sewing-Machines, of which the following is a description, reference being had to the accompanying drawing and to the figures of 10 reference marked thereon.

The invention relates to new and useful improvements in tape guides for sewing machines, and more particularly to a tape 15 guide which may be readily adjusted to guide tapes of different widths.

In certain classes of work, it is desirable to stitch simultaneously a plurality of tapes to a fabric, and these tapes are stitched on a multiple needle stitching machine. An object of the present invention is, therefore, to provide a tape guide for a multiple needle machine, which tape guide is capable of simultaneously guiding tapes and directing the same to the respective needles, and wherein 25 said tape guide may be quickly adjusted so that all tape guiding sections may be simultaneously varied to the same extent for a series of tapes of a different width.

A further object of the invention is to provide a tape guide for sewing machines, which tape guide includes a cylindrical member having a circumferential groove of varying width, together with means whereby a section of said groove is made operative 30 for guiding a tape to the stitching mechanism, and wherein the cylindrical member may be adjusted about its axis to vary the width of the portion presented for guiding the tape.

These and other objects will in part be obvious and will in part be hereinafter more fully disclosed.

In the drawings, which show by way of illustration one embodiment of the invention:—

Figure 1 is a front view of a portion of a sewing machine having my improved tape guide applied thereto;

Fig. 2 is an end view of the same;

Fig. 3 is a view, partly in section and partly in plan, showing a part of the work support and presser foot having my improved tape guide;

Fig. 4 is a vertical sectional view on the 55 line 4—4 of Fig. 3;

Fig. 5 is a bottom plan view of the presser foot with the tape guide carried thereby;

Fig. 6 is a sectional view through the presser foot centrally of the tape guiding member, showing the tape guiding member 60 for guiding a series of tapes of a given width.

Fig. 7 is a similar view, but showing the tape guiding member adjusted for guiding a series of tapes of a different width;

Fig. 8 is a sectional view on the line 8—8 of Fig. 6, the tape and fabric being omitted; and

Fig. 9 is a perspective view of the tape 70 guiding member.

In carrying out the invention, I have provided a tape guiding member which is preferably cylindrical in form and which is provided with a series of circumferential grooves which extend into the surface of the 75 cylindrical member sufficiently to form tape guiding walls. Each of these circumferential grooves is constructed so that it varies in width, this variation being preferably uniform. The cylindrical member is mounted in the presser foot of the sewing machine in advance of the needles, and the presser foot is provided with means for directing a tape so that a section of the groove 80 becomes effective for guiding the tape which 85 is being stitched. The directing means on the presser foot is of sufficient capacity to take a tape of the widest width that can be guided by the cylindrical tape guiding member so that this cylindrical member becomes 90 the active means for guiding the series of tapes to the respective needles. It is often desirable to stitch a series of tapes of a different width. This may be readily accomplished by adjusting this cylindrical member 95 so as to present a tape guiding surface which is of proper width to guide the series of tapes which it is desired to stitch to the fabric. The cylindrical member is for this purpose adjustable about its axis, and means 100 is provided for holding it in an adjusted position.

Referring more in detail to the drawings:—

I have shown my invention applied to a 105 sewing machine which is formed with a work support 1, an overhanging arm 2 carrying a needle bar 3, in which is mounted a series of needles 5. As herein shown, there are five needles. Coöoperating with each nee- 110

dle beneath the work support is a looper 6. Each needle and coöperating looper is entirely independent of the other needles and their coöperating loopers.

5 The material is fed across the work support by a feed dog 7 which may be of the usual construction. The material is held on the work support by a presser foot 8 carried by a presser bar 9 mounted in the overhanging arm 2 in the usual manner. The presser foot is provided with a series of needle openings 10, one for each needle. The presser foot is also formed with a slot 11 which extends across the presser foot and which is located directly in front of the needle openings 10.

10 Mounted in the slot 11 is a cylindrical tape guiding member 12. The presser foot is formed with a raised portion 13 at one side thereof, and a supporting pivot screw 14 extends through this raised portion and is threaded centrally into the cylindrical member 12, as clearly shown in Figs. 6 and 7 of the drawings. The other end of the cylindrical member extends into a socket 15 formed in the raised portion 16 of the presser foot. A set-screw 17 carried by this raised portion 16 is adapted to clamp the cylindrical portion and hold it in an adjusted position. Said cylindrical portion 12 is formed with a slot 18 for a screw-driver to facilitate the adjustment of the same.

15 This cylindrical member 12 is formed with circumferential grooves 19. There are five grooves, one for each tape. These grooves are of similar construction, and only one groove will, therefore, be described in detail. The groove extends into the cylindrical member so as to form side walls 20 and 21. The groove varies in width. Extending longitudinally of the member 12 is a groove 22, and the groove 19 extends into this longitudinal groove 22. The maximum width of the groove 19 is at one side of the groove 22, while the minimum width is at the other side thereof, and the groove varies uniformly in width between the maximum and minimum widths referred to. The presser foot carries a plate 23, which extends 25 from end to end thereof in front of the cylindrical member 12, and this plate is formed with spaced guiding recesses 24, one for each groove 19, and the width of each recess 24 is the maximum width of the groove with 30 which it coöperates.

35 In Fig. 3 of the drawings, I have shown a series of tapes, indicated at T. Each tape is directed through a recess 24, and then passes through the section of the groove 19 which is substantially on the under face of the cylindrical member 12. The member 12 is turned until the section of the groove presented for guiding the tape is of the width of the tape, and the tapes led in through the 40 recesses 24 will be properly directed by the

grooves 19 so that the needles will form a line of stitching centrally through the respective tapes.

When it is desired to change to a series of tapes of different widths, the member 12 70 is turned until the section of the groove is brought into tape guiding position which is of the width of the tape desired to be stitched. It will be noted that all the 75 grooves will be simultaneously adjusted so that the operator may go quickly from a series of tapes of one size to a series of tapes of a different size. It will also be noted that the tape guide is mounted on the presser foot and is raised and lowered therewith, which 80 greatly facilitates the insertion of the material underneath the same and the removal of the material after the tapes are stitched thereto.

85 It is obvious that minor changes in the details of construction and the arrangement of parts may be made, when desired, without departing from the spirit of this invention, as set forth in the appended claims.

Having thus described the invention, what 90 is claimed as new is:—

1. The combination with a multiple needle stitching mechanism, of a series of tape guides for independently guiding tapes to the stitching mechanism, and means for 95 simultaneously varying the capacity of the several tape guides.

2. The combination of a multiple needle stitching mechanism, a presser foot, a series of tape guides mounted on the presser foot 100 for independently guiding tapes to the stitching mechanism, and means for simultaneously varying the capacity of the several tape guides.

3. The combination with a multiple stitching mechanism, of a presser foot having 105 tape guiding recesses, a series of tape guides for receiving the tape from said recesses and for directing the same to the needles of the stitching mechanism, and means for simultaneously varying the capacity of the several 110 tape guides.

4. The combination with a multiple stitching mechanism, of a presser foot having a series of tape guiding recesses, a cylindrical 115 member having a series of circumferential grooves adapted to receive the tapes from said recesses respectively and for guiding the tapes to the needles of the stitching mechanism, said grooves being of varying 120 width, and means for adjusting the cylindrical member for presenting different tape guiding sections of the groove into operative relation with said guiding recesses.

5. A tape guide comprising a cylindrical 125 guiding member having a tape guiding groove extending circumferentially about the same, said groove being of varying width, means coöperating with said member whereby a portion of said groove may be 130

utilized for guiding a tape, means for supporting said member, and means whereby said member may be turned about its center axis for varying the width of the portion 5 presented for guiding the tape.

6. A tape guide comprising a cylindrical guiding member having a series of spaced tape guiding grooves extending circumferentially about the same, each of said grooves 10 being of similar construction and of varying width, means coöperating with said member whereby the same corresponding

portion of each groove may be utilized to guide tapes of the same width, means for supporting said member, and means whereby said member may be turned about a central axis for adjusting the same to receive a series of tapes of different width. 15

In testimony whereof, I affix my signature, in the presence of two witnesses.

JOSEPH L. STENGEL.
